UNITED STATES PATENT OFFICE.

JOHN N. ANDERSON, OF HOBOKEN, NEW JERSEY, ASSIGNOR TO OTIS ELEVATOR COMPANY, OF JERSEY CITY, NEW JERSEY, A CORPORATION OF NEW JERSEY.

ELEVATOR SAFETY APPLIANCE.

Application filed August 17, 1926. Serial No. 129,748.

The invention relates to safety appliances for elevators and particularly to safety appliances adapted to be applied to a stationary rail for bringing a moving body of the elevator system to a stop in the event of its traveling above a predetermined speed.

One feature of the invention is to provide a safety appliance which, when actuated, operates to apply a substantially constant 10 retarding force in predetermined amount to bring a moving body to a stop.

Another feature lies in the provision of a safety appliance which, after it has been applied to stop a moving body, will be released upon movement of the body in the reverse direction.

Still another feature is the provision of a safety appliance of the above character which is of simple construction, reliable in 20 operation and which may be operated an unlimited number of times without replacement.

Other features and advantages will become apparent from the specification, taken 25 in connection with the accompanying drawings wherein one embodiment of the invention is illustrated.

In the drawings:

Figure 1 is a schematic representation of 30 an elevator system illustrating the adaptation of the safety appliance to an elevator car;

Figure 2 is a view in partial section, taken along the line 2—2 of Figure 1;

Figure 3 is a sectional view taken along the line 3—3 of Figure 1;

Figure 4 is a view in partial section, taken along the line 4—4 of Figure 1; and

Figure 5 is a view in partial section, taken 40 along the line 5—5 of Figure 4.

Referring to Figure 1, the elevator car is designated by the numeral 1 while the counterweight is designated by the numeral 2. Hoisting ropes 3 for the car and counterweight pass over the hoisting drum 4 at the top of the elevator shaft. This drum is driven by means of the hoisting motor 5 to effect the raising and lowering of the car and counterweight. An electromagnetic 45 brake 6 is employed for bringing the motor, and therefore the car and counterweight, to a stop. Guide rails 7 are provided for the elevator car and guide rails 8 for the counterweight. The bottom guide shoes for

the car are designated 12 while the top 55 guide shoes are designated 13. The counterweight guide shoes are designated 14. A governor rope 15 extends around a tensioning sheave 16 that has a weight 17 mounted in the guides 18 at the bottom of the hatchway. From the sheave 16 the governor rope extends upwardly and over the sheave 20 of a centrifugal governor 21. The governor 21 is of the flyball type wherein the ball carrying arms 22 are connected through 60 links 23, sleeve 24, lever 25 and link 26 to the arm 27 of a jaw 28. Jaw 28 is pivotally mounted on a shaft 30 and is geared to a co-acting jaw 31. Jaw 31 is pivotally mounted at 32 on a rod 33 that is slidably carried in 65 a guide support 34. A spring 35 surrounds the rod 33 and urges jaw 31 toward jaw 28. From the sheave 20 the governor rope extends downwardly between the jaws 28 and 70 31. These jaws are arranged to grip the 75 governor rope upon the operation of the governor 21. A spring pressed latch 36 engages the arm 27 and prevents the jaws from engaging the governor rope until the governor 21 operates through link 26 to effect 80 the release of this latch.

According to the preferred arrangement, the ends of the governor rope 15 are connected by yokes 37 to an arm 29 of a bell crank lever 38 pivotally mounted on a shaft 85 40 extending from the channel members 48 and 59 of the car frame. The other arm of the lever 38 extends upwardly and is pivotally attached to a lock bar 41 by means of a screw 39 extending through the arm and 90 threaded into the lock bar. The lock bar 41 is carried by a releasing bracket 42 secured to the car frame. As illustrated in Figure 2, the lock bar 41 is positioned within an aperture 43 in the releasing bracket. The lock bar is of rectangular cross section and is formed with a boss 14 at one side thereof. This boss is provided with a recess 49 in which rests the cylindrical face of a releasing jaw 45. The jaw 45 extends through an aperture 46 in the releasing bracket and is held in contact with the lock bar by a bolt 47. Bolt 47 extends through an aperture in the jaw 45, through a slot in the lock bar 41, through an aperture in the releasing bracket and through the channel member 48 of the car frame. The end of the bolt 47 extending beyond mem- 100 105

ber 48 is surrounded by a compression spring 50 having spring seats 11 and 19. This spring acting through the seats 11 and 19 bears at one end against the channel member 5 and at the other end against the nut 51 threaded on the bolt. By adjusting the nut 51 and cotter pin 52 along the bolt 47, the force of the spring 50 and the resulting pressure exerted by the jaw 45 against the lock 10 bar 41 may be varied.

Referring again to Figure 1, a lift rod 53 has its upper end extending through the arm 29 of the bell crank lever 38. Nuts 54 are threaded on the end of the lift rod 53 adjacent the arm 29 and serve to secure this rod to the arm 29. The lower end of the lift rod is pivotally connected to a lever 55. Lever 55 is keyed to a rock shaft 56 that is supported in bearings 57 and 58 formed on the 20 guide clamp housings 60 and 61 of two guide clamps 64 and 65. Guide clamp housings 60 and 61 carry the lower guide shoes 12 and are secured to the opposite ends of the safety plank 62 of the car frame by means of screws 25 63. A lever 69, similar to the lever 55, is keyed to the rock shaft 56 adjacent the bearing 58.

Guide clamps 64 and 65 are of similar construction. The construction of one of these 30 guide clamps, i. e., clamp 64, is illustrated in Figures 3, 4 and 5. Guide clamp 64 comprises two jaw members 66 and 67 that are pivotally mounted on the central portion of a vertically extending shaft 70. A bushing 68 is positioned between the jaw members and the shaft 70. Jaw member 67 is formed with two pivotal lugs 73 and 74 that encircle the bushing 68 and extend over similar pivotal lugs 75 and 76 formed on jaw member 40 66. The jaw members are retained on the shaft 70 by a nut 71 threaded on the reduced lower portion of the shaft and locked thereon as by a cotter pin. A washer 72 is interposed between jaw member 67 and nut 45 71. The upper portion of the pivotal shaft 70 is reduced in diameter and extends through and beyond the housing 60. The portion of the shaft 70 that extends beyond the housing 60 is threaded and has a nut 77 thereon for securing the shaft 70 rigidly to the housing. A cotter pin 78 locks the nut 77 to the shaft 70.

The portion of the jaw member 66 that is 55 opposite the guide rail 7 is formed with a vertically extending semi-cylindrical recess 80. A wedge 81 having a semi-cylindrical bearing surface corresponding to the recess 80 lies against the jaw member 66 within the recess 80 and is free to swivel therein. 60 The inclined surface of the wedge 81 faces the guide rail 7 and is formed with a depression in its lower portion to conform to the surface of a roller 82. The wedge 81 is formed with a recess 84 at its upper end into 65 which recess extends a stop plate 83 for re-

taining the wedge on the jaw member 66. The stop plate is secured to the housing 60 by screws 85. The lower end of the wedge rests on a bracket 86 attached by screws 87 to the jaw member 66. The roller 82 is carried by a frame 88 pivotally mounted on a boss 96 formed on the end of the lever 55. The frame 88 comprises a pivotal pin 94 passing through the roller 82 and connected at its ends to two side plates 90 and 91 that 70 are rotatably mounted on axially aligned screws 92 and 93 threaded into the boss 96. Screw 92 also serves to connect the lift rod 53 to the lever 55. The boss 96 is cylindrical in form and its upper curved surface 80 is abutted by the roller 82. As this surface is concentric with the screws 92 and 93, swinging movement of the frame 88 with respect to the lever 55 causes the roller 82 to roll on the surface of the boss 96. The lift rod 53 is grooved at 95 to accommodate the end of the pin 94. The bracket 86 is formed with a hooked portion 97 upon which the lower surface of the boss 96 rests. A stop bracket 100 is secured to the under surface 90 of the jaw member 67 and is formed with a horizontal beveled portion 101 extending parallel to the side of the guide rail. This beveled portion 101 engages one side of the roller 82 and retains it away from the guide 95 rail and against the lower depressed surface of the wedge 81.

The portion of the jaw member 67 that is opposite the guide rail 7 is formed with a surface 102 that is inclined to the guide rail. 100 A dovetail guideway 103 is provided on this inclined surface and accommodates the dovetail tongue 104 of a releasing wedge 105. Inasmuch as the jaw member 67 and the releasing wedge 105 are normally constructed 105 of the same material, it is desirable, in order to avoid excessive wear, that the sides of the dovetail guideway 103 and the tongue 104 be constructed of a different and preferably a softer material. Thus should the 110 jaw member and the releasing wedge be made of steel, the sides of the guideway and the tongue 104 would be constructed of some such material as brass. In this case the sides of the guideway and the tongue are secured 115 to their respective parts as by screws 106. The releasing wedge 105 is provided with a cylindrical recess 107 extending parallel to the inclined surface of the jaw member 67 for a portion of the length of the wedge. 120 A bracket 110 is secured to the jaw member 67 by screws 111 and has a pin 112 extending upwardly into the recess 107. A compression spring 108 surrounds the pin 112 and extends into the recess 107. This spring bears at one end against the bracket 110 and at the other end against the inner end of the recess 107 and urges the releasing wedge 105 upwardly. A projecting web 145 is formed 125 on jaw member 67 and is adapted to engage 130

an abutment 146 formed on jaw member 66 when the guide clamp is in disengaged position.

The ends of the jaw members 66 and 67 that are farther from the guide rail 7 have a compression spring 113 interposed between them. A spring seat 114 is interposed between spring 113 and jaw member 66 while a washer 115 is interposed between this spring and jaw member 67. A bolt 116 extends through spring seat 114, spring 113, washer 115, and an aperture 117 in jaw member 67. The head of bolt 116 extends into a rectangular recess 118 formed in the member 66 and is prevented from turning therein by engagement with the sides of this recess. The portion of the bolt 116 that extends beyond the jaw member 67 has a washer 126 and a nut 127 retained as by a cotter pin thereon. Spring 113 may be placed under no initial compression or under any initial compression that may be desired by varying the thickness of washer 115. A semi-annular web 120 formed on the member 66 at one side of the spring seat 114 and a plate 121 secured to the member 66 by bolts 122 at the other side of such seat, serve to retain the spring seat and therefore the spring in proper position on the member 66. Likewise a semi-annular web 123 formed on the member 67 and a plate 124 secured to the member 67 by bolts 125, serve to retain the washer 115 and the spring in proper position on this member.

35 A lug 128 provided on the jaw member 67 is apertured and has a bolt 130 extending therethrough. This bolt also extends through and beyond an aperture 131 in an angle bar 132. Angle bar 132 is secured by bolts 133 to another angle bar 134 extending across the lower side of the safety plank 62 of the car frame. The bar 134 is affixed to the safety plank 62 by bolts 135. The portion of the bolt 130 extending beyond the aperture 131 in the bar 132 is surrounded by a compression spring 136. Spring 136 bears at one end against the bar 132 and at the other end against a washer 137 positioned adjacent the head of the bolt. Nuts 138 and 140 and a washer 141 are positioned on the shank of the bolt 130 adjacent the lug 128 for varying the compression of spring 136. This construction serves to maintain the clamp structure as a unit against stop plate 83. Thus, stop plate 83 not only serves as means for maintaining the wedge 81 against jaw member 66 but also as a stop for the clamp structure.

In operation the car moving up and down the hatchway acts through lever 38 to cause a corresponding movement of the governor rope 15. This rope passing over the sheave 20 effects rotation of the governor 21. Governor 21 is set so that, as long as the descending car does not exceed a certain speed,

the governor does not operate to cause the jaws 28 and 31 to grip the governor rope. In the event that the speed of the car exceeds this certain speed, the governor operates through link 26 to overcome the latch 70 36 and effect the release of jaws 28 and 31. These jaws, turning about their pivotal shafts, fall under the influence of gravity and grip the governor rope with a pressure determined by the force of spring 35. The 75 motion of the governor rope is retarded causing the arm 29 of the bell crank lever 38 to swing upwardly with respect to the car. This upward movement of the arm 29 can only be accomplished, however, by the bell 80 crank 38 pushing the lock bar 41 inwardly of the releasing bracket 42. This movement of the lock bar 41 forces the releasing jaw 45, against the pressure of spring 50, out of the recess in the lock bar. As arm 29 swings upwardly, it raises lift rod 53 and causes the lever 55 connected to the lower end of the lift rod to also swing upwardly. Inasmuch as lever 69 is connected through rock shaft 56 to lever 55, this upward swinging movement of lever 55 will cause a simultaneous upward swinging movement of lever 69. The upward swinging movement of these levers 55 and 69 causes the operation of 95 guide clamps 64 and 65. As these guide clamps operate in a similar manner, the operation of only one of them, i. e., clamp 64 will be described.

As lever 55 swings upwardly, it carries the frame 88 and connected roller 82 upwardly 100 also. Roller 82 leaves the depression in wedge 81 and rides along the inclined face of this wedge toward the guide rail. Upon engaging the rail 7, the roller 82 rolls thereon and swings the jaw members as a unit 105 about the shaft 70, thus moving the releasing wedge 105 into engagement with the guide rail, whereupon further movement of the member 67 is prevented. Continued upward movement of the roller 82 causes an increasing compression of the spring 113 and a corresponding increase in the frictional force of the roller 82 and the releasing wedge 105 upon the guide rail. On approaching the upper end of the wedge 81 the 115 roller 82 strikes the stop plate 83 and can no longer move upwardly with respect to the wedge and hence cannot further compress the spring 113.

The guide clamp thus grips the guide rail 120 with a predetermined elastic force, causing the dissipation of the kinetic energy of the car. The car is caused to come smoothly to rest, in a suitable distance, and without excessive deceleration. Inasmuch as the roller 125 rolls on the guide rail and slides against the wedge 81, it does not abrade the guide rail. Owing to the freedom of the roller engaging wedge to swivel in the jaw member and the elasticity of the spring urging 130

the jaw member against the guide rail, the guide clamp automatically adjusts itself to any unevenness of the guide rail.

When it is desired to release the guide clamp from the guide rail, it is only necessary to energize the hoisting motor 5 so as to move the car in the up direction. As the car starts to move in the up direction, the releasing wedge 105 remains stationary on the guide rail, owing to the frictional force between the wedge and the guide rail. It is to be noted that the angle of the inclined surface of the wedge 105 must be sufficient to permit this wedge to slide with respect to the jaw member. Furthermore the angle must not be so great that the wedge will slide on the jaw during the application of the safety appliance. It has been found that a suitable angle for wedge 105 lies between eight degrees and fifteen degrees. The surface 102 of the jaw member 67 slides upwardly along the inclined surface of the releasing wedge and toward the guide rail, causing the member 67 to turn about the shaft 70. The spring 108 is thus compressed between the releasing wedge and the bracket 110 by this movement of the jaw member 67 with respect to the releasing wedge. The swinging movement of the jaw member 67 permits the spring 113 to expand, causing a diminution in the force exerted by the roller 82 against the guide rail. The frictional forces exerted upon the roller 82 by the wedge 81 and the guide rail are thus reduced, permitting this roller to roll upon the guide rail and slide along the wedge 81 away from the stop plate 83. This motion of the roller 82 by permitting further expansion of the spring 113 causes a corresponding reduction in the force exerted by the roller against the guide rail. As the roller comes to rest between the stop bracket 100 and the depressed lower portion of the wedge 81, the frictional force exerted by the guide rail upon the releasing wedge 105 will be eliminated. The compressed spring 136 acting upon the jaw member 67, through the medium of bolt 130, now causes this member to swing about the shaft 70 and effects the separation of the releasing wedge from the guide rail. As this wedge moves from the guide rail, the compressed spring 108 expands, causing the releasing wedge to slide upwardly along the surface 102 of the jaw member 67 until the upper end of this wedge abuts the housing 60.

The guide clamp is now in its disengaged position. The manual resetting of jaws 28 and 31 of the governor 21 and the replacing of the releasing jaw 45 within the recess 49 of the lock bar 41, places the wedge clamp in condition for another operation.

Since the roller 82 is secured by the frame 88 to the lever 55, this roller cannot escape from the guide clamp.

The safety clamp may be operated many times without the necessity of replacing any parts of either the safety appliance or of the elevator apparatus.

This safety appliance may equally as well be applied to the counterweight and thus prevent excessive car speed in the up direction.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. In an elevator system; a body movable in the hatchway; guide rails for said movable body; and means carried by the movable body for gripping the guide rails, said gripping means comprising jaw members; means associated with certain of said jaw members for effecting an engagement between the jaw members and the guide rails; and means associated with others of said jaw members for effecting the release of said jaw members from the guide rails. 85
2. In an elevator system; a body movable in the hatchway; guide rails for said movable body; and means carried by the movable body for gripping the guide rails, said gripping means comprising jaw members; means associated with certain of said jaw members for effecting an engagement between the jaw members and the guide rails with said body moving in one direction; and means associated with others of said jaw members for effecting the release of said jaw members from the guide rails upon movement of said body in the other direction. 90
3. In an elevator system; a body movable in the hatchway; guide rails for said movable body; and means carried by the movable body for gripping the guide rails, said gripping means comprising jaw members, antifriction means for effecting an engagement between the jaw members and the guide rails, and wedge means for effecting the release of said jaw members from the guide rails. 100
4. In an elevator system; a guide rail; a body movable along said guide rail; and a safety appliance for said movable body comprising, a housing carried by said movable body, two jaw members pivotally carried by said housing and arranged at opposite sides of said guide rail, a roller positioned between one jaw member and a side of the guide rail and movable with respect to the jaw member, a wedge positioned between the second jaw member and the other side of the guide rail and movable with respect to said second jaw member. 110
5. In an elevator system; a guide rail; a body movable along said guide rail; and a safety appliance for said movable body comprising, a housing carried by said movable body, two jaw members pivotally carried by said housing and arranged at opposite sides of said guide rail, a roller positioned between one jaw member and a side of the guide rail and movable with respect to the jaw member, a wedge positioned between the second jaw member and the other side of the guide rail and movable with respect to said second jaw member. 120
6. In an elevator system; a guide rail; a body movable along said guide rail; and a safety appliance for said movable body comprising, a housing carried by said movable body, two jaw members pivotally carried by said housing and arranged at opposite sides of said guide rail, a roller positioned between one jaw member and a side of the guide rail and movable with respect to the jaw member, a wedge positioned between the second jaw member and the other side of the guide rail and movable with respect to said second jaw member. 125
7. In an elevator system; a guide rail; a body movable along said guide rail; and a safety appliance for said movable body comprising, a housing carried by said movable body, two jaw members pivotally carried by said housing and arranged at opposite sides of said guide rail, a roller positioned between one jaw member and a side of the guide rail and movable with respect to the jaw member, a wedge positioned between the second jaw member and the other side of the guide rail and movable with respect to said second jaw member. 130

5. In an elevator system; a guide rail; a body movable along said guide rail; and a safety appliance for said movable body comprising, a housing carried by said movable body, two jaw members pivotally carried by said housing and arranged at opposite sides of said guide rail, a roller positioned between one jaw member and a side of the guide rail and movable with respect to the jaw member, a wedge positioned between the second jaw member and the other side of the guide rail and movable with respect to said second jaw member, mechanism for moving said roller with respect to the first jaw member to effect the operation of said safety appliance, motive means for causing said wedge to move with respect to the second jaw member to effect the release of said safety appliance, and spring means for resisting the movement of the wedge with respect to the second jaw member.
10. In a safety appliance for elevators; a housing; a jaw member pivotally mounted on said housing and arranged to cooperate with one side of a guide rail; and a wedge mem-
- ber positioned between the guide rail and the jaw member, said jaw member and said wedge member moving as a unit to cause the wedge member to engage the guide rail upon the application of the safety appliance and said wedge member moving with respect to the jaw member to disengage the guide rail upon the release of the safety appliance.
15. In a safety appliance for elevators; a housing; a jaw member pivotally mounted on said housing and arranged to cooperate with one side of a guide rail, said jaw member having a guideway; a wedge member positioned between the guide rail and the jaw member, and having a tongue extending into the guideway of the jaw member; spring means for positioning the wedge member with respect to the jaw member; and a second jaw member pivotally mounted on the housing and arranged to cooperate with the other side of the guide rail.
20. In a safety appliance for elevators; a housing; a jaw member pivotally mounted on said housing and arranged to cooperate with one side of a guide rail; and a wedge mem-
- ber positioned between the guide rail and the jaw member, said jaw member and said wedge member moving as a unit to cause the wedge member to engage the guide rail upon the application of the safety appliance and said wedge member moving with respect to the jaw member to disengage the guide rail upon the release of the safety appliance.
25. In a safety appliance for elevators; a housing; a jaw member pivotally mounted on said housing and arranged to cooperate with one side of a guide rail; and a wedge mem-

In testimony whereof, I have signed my name to this specification.

JOHN N. ANDERSON.
